FLOATING CATHODE AMPLIFIER

Theodorus H. Nakken, Brooklyn, N. Y., assignor
to Nakken Patents Corporation, a corpora-
tion of Delaware

Application June 12, 1929. Serial No. 370,294

2 Claims. (Cl. 179—171)

This invention relates to amplifiers. The object of the invention is to effect amplification of feeble electric impulses into substantially corresponding power impulses. In carrying out this general object of the invention it is proposed to maintain a substantially fixed plate potential; to provide means tending to maintain the potential of each grid the same as that of its corresponding cathode; and to permit cathodes and grids to fluctuate as to their potential in response to the signalling impulses and relatively to the substantially fixed potential of the plates.

In embodying my invention I contemplate the employment of thermionic triode amplifier tubes of the type employing an electron emitter or cathode locally heated by a separate heater and itself insulated from such heater and free from any substantial capacity coupling therewith.

The claims are directed to illustrative embodiments of the invention solely for purposes of illustration and not limitation. These embodiments are described in the following specification in connection with the accompanying drawings which form a part hereof.

In the drawings, Fig. 1 is a diagram illustrating one form of the invention; and Fig. 2 is a similar diagram illustrating the invention in a modified form.

In my amplifier assemblage I employ a plurality of thermionic triode amplifiers A, A₁, A₂ and A'₂, each comprising a plate P, a grid G, and a cathode C. I preferably employ the type of tube in which the cathode C is heatable to a state of electron emission by a separate heating element insulated from the cathode and with the cathode free from capacity coupling with its heater. Preferably the tubes A₂ and A'₂ are of the power type. The secondary 1 of an input transformer 2 has its terminals connected respectively to the cathodes and the grid of tube A.

In Fig. 1, a conductive lead 3 connects one terminal of secondary 1 with cathode C while a condenser 4 serves as a link means to connect the opposite terminal with the grid G.

In Fig. 2, the capacity link and the conductive link are reversed in position as indicated by the conductive link 3 and the condenser 4.

Between the stage A and A₁ is provided an inter-stage transformer 21. Its primary is directly connected with the cathode C from the negative terminal 20 of a suitable source of direct current plate potential. Its secondary has its terminals connected respectively by a conductive connection 31 and a condenser link 41 with the cathode and grid of tube A₁. The primary of a third trans-

former 2₂ connects the negative terminal 20 of the plate circuit source with the cathode C of tube A₁ while its secondary is in the form of two separate coils 1₂ and 1'₂. The terminals of each of these separate coils are connected respectively by means of a conductive link 3₂ and capacity link 4₂ with the cathode and grid of tube A₂ while the terminals of coil 1'₂ are respectively connected by conductive link 3'₂ and capacity link 4'₂ with the cathode and the grid of tube A'₂. Respective cathodes C of tubes A₂ and A'₂ are connected to opposite terminals of the two-part primary 5 and 5', the center point of which is connected through main 6 with the negative terminal 20. The secondary 1₂ of this transformer supplies power to any desired translating device.

In the amplifier of Fig. 1, each grid is connected by its respective high resistance or leak resistance R, R₁, R₂ and R'₂ with the negative terminal 20.

The plates of tubes A and A₁ are both connected to the plus 90 terminal of the plate current source while the plates P of tubes A₂ and A'₂ are connected to the plus 450 terminal of the plate current source.

Referring now more particularly to Fig. 2, the same connections except that the conductive and capacity link means between each transformer secondary and the associated cathode and grid of the tubes which they control are reversed from the connections shown in Fig. 1. In addition, the leak resistances R, R₁, R₂ and R'₂ are connected between the negative terminal 20 and the terminal of the transformer secondary farthest from the grid G at a point preferably adjacent to the condenser operation with no excitation of the cathodes to effect electron emission and with no signal coming through the amplifier. All cathodes and grids are at the same potential, preferably the full negative of the system as indicated by the connections described. The plates are all conductively directly connected to their proper value positive voltage terminal. Upon excitation of the cathodes into a state capable of emitting electrons, these cathodes as well as the controlling grids G float as to their potential in response to signal variations while the transformer secondaries fulcrum on the potential of the cathode to which they are connected and apply to the associated grid a potential relatively to the cathode which fluctuates in accordance with the terminal fluctuation of the said transformer secondaries.

What I claim and desire to secure by United States Letters Patent is:

1. In combination in an amplifier assemblage, a triode thermionic amplifier comprising a cathode having a separate heater, a plate and a grid; an input transformer having a secondary coil well insulated from its core and primary winding; a source of direct current plate circuit potential having a negative terminal and a positive terminal; an output transformer having a primary coil; electric connections connecting the plate of said triode amplifier to the positive terminal of said source of direct current potential and said primary coil between the cathode of said triode amplifier and said negative terminal of said source of direct current potential; said secondary coil having terminal connections to the cathode and to the grid of said triode amplifier including a condenser; and a leak resistance conductively connecting the grid of said triode amplifier with said negative terminal and leaving said cathode free from conductive connection with said negative terminal by the interpositioning of said condenser, except that said cathode is connected to the free high potential end of the primary coil of said output transformer and is free to partake of the instantaneous potentials thereof.
2. In a thermionic triode amplifier assemblage, a plurality of triode amplifiers each comprising a plate, a grid and a cathode having an electrically separate heating element; a source of direct current plate circuit potential having a negative terminal and a positive terminal; a direct conductive connection between said positive terminal and the plates of said triode amplifier; a transformer coil connected between each said cathode and said negative terminal, each said cathode being maintained free from any direct connection with ground and with said source of direct current plate circuit potential; a leak resistance connecting each said grid with said negative terminal; and an input coil; link means connecting the ends of said coil respectively to the grid and the cathode of each said triode amplifier including a condenser between said cathode and one end of said coil, whereby in response to signals the cathode and grid potentials fluctuate relatively to each other.
